his Attorneys.

UNITED STATES PATENT OFFICE.

JOHN L. TANDY, OF KANSAS CITY, MISSOURI.

COOLING DEVICE.

Application filed August 24, 1921. Serial No. 495,140.

To all whom it may concern:

Be it known that I, JOHN L. TANDY, a citizen of the United States, residing at Kansas City, in the county of Jackson and State of Missouri, have invented a certain new and useful Improvement in Cooling Devices, of which the following is a complete specification.

The present invention relates to cooling or refrigerating devices, and aims to provide a simple form of cooling means adapted to be applied in the form of a convenient attachment to ordinary types of receptacles, such as pails, pans, crocks, and the like, or used, if preferred, as a direct container for the articles to be kept cool.

Accordingly, I have devised a cooling device in the form of a covering or casing made of suitable fabric material having a water receptacle or chamber associated therewith and adapted to feed this water gradually through the fabric material forming the covering or casing in such a manner that a wet or damp zone is maintained substantially surrounding the receptacle to be cooled; in this way constant evaporation of the moisture is maintained around the outer surface of the receptacle, and hence the usual cooling effect always attending such an evaporating process is caused to take place.

With the foregoing general object in view, the invention will now be described by reference to the accompanying drawing illustrating the improved cooling device as adapted to be applied in its various forms, after which the novel features therein will be specifically set forth and claimed.

In the drawing—

Figure 1 is a perspective view illustrating a pail having a cooling device embodying the present improvement applied to the exterior thereof, a portion of said device being broken away;

Figure 2 is a similar view illustrating the device in a modified form, and applied to a slightly different form of receptacle;

Figure 3 is a perspective view illustrating the cooling device as applied to a common form of crock receptacle;

Figure 4 is a sectional view of the cooling device as represented by the form shown in Figure 3;

Figure 5 is a perspective view of a basket form of receptacle having the present improvement applied thereto;

Figure 6 illustrates a perspective view of

another form of cooling device embodying the invention adapted to be applied to a cylindrical form of receptacle;

Figure 7 is a detail perspective view showing a portion of the improved cooling device in a modified form of water containing chamber; and

Figures 8 and 9 are plan and side views showing a modified form of top or cover structure.

Referring now to the drawing in detail, this illustrates the improved form of cooling or refrigerating device as comprising a sheet of suitable fabric material, such as canvas or the like, made up in the form of a casing or covering with the body portion 10 thereof in the required shape to conform to and produce a covering or enclosure for the receptacle, as illustrated in the various views of the drawing; in Figure 1, the receptacle 12 is of substantial cylindrical form, to which the device is fitted in the manner of an attachment applied to the exterior of the receptacle. The device also includes what may be termed a water receptacle or chamber which I have found it convenient to construct by producing a roll 14 extending entirely around some portion of the covering or casing 10, as illustrated in Figures 1 to 3, and 5 of the drawing, and preferably around the top of said casing or covering, as illustrated in Figures 1, 3 and 5. This roll 14 may be formed in any preferred manner, as by rolling back the fabric material and stitching it in the form illustrated, or by applying and securing an extra piece of the material in an obvious manner for producing the required annular water chamber, indicated by the reference numeral 15 in Figure 4. At some point along the roll 14 I also provide a filling-spout 16 having a removable cap 17, whereby water may be introduced into the chamber 15 as often as required.

In each case, according to the type of receptacle involved which is to be cooled, the covering or casing 10 is shaped to conform to the receptacle, Figure 2 of the drawing showing a plain cylindrical form of receptacle 12^a, in which case the casing 10 may have its roll 14 for the water chamber located somewhat below the top of the receptacle, as shown, and in most cases it is desirable to apply a top or closure, such as illustrated at 18, to the top of the receptacle, the closure 18 being of a type adapted to be se-

100

115

cured by means of a draw string 19 engaging around beneath the bead or rim of the receptacle in an obvious manner. Figure 3 of the drawing shows the device as adapted to conform to the shape of a crock 12^b, with the roll 14 of the device fitted snugly beneath the flange portion forming the rim of the receptacle. In Figure 5 of the drawing, I illustrate the improved cooling device as adapted for use in connection with a basket, such as any ordinary form of market basket 20, in which case the device may be made in the form of a receptacle adapted to be fitted inside the basket or basket frame 20, and provided with a roll 14 for the water chamber around the upper margin of the basket, as shown.

Figure 6 illustrates a modified form of device, in which the same is provided with an outwardly flared portion, as indicated at 22 at its upper edge, for forming a water chamber 23 between this flared portion and the upper edge of the body portion 10, thus dispensing with the use of the rolls illustrated at 14 in the other views of the drawing, and providing such rolls only as they may be required for the formation of branch channels to facilitate the spread of the water from the chamber 23 to all parts of the fabric material 10 forming the casing or covering for the receptacle. In the view shown in Figure 6, I illustrate a plurality of vertical roll portions 14' for providing as many vertical branch channels for the distribution of the water from the chamber as may be desired. This type may be used to advantage in the basket form Figure 5.

In Figure 7 is illustrated a modified form of construction for the water chamber, in which a tubular member 25 of suitable material (such as sheet metal or rubber), and having a set of openings or perforations 26, is inserted within the roll 14 of the device, thus providing a more rigid construction which may be preferred in some conditions. The operation is substantially the same, of course the water simply percolating through the perforations 26 and out through the fabric material of the device, as with the other form of construction shown.

It is thus apparent that I have devised a simple and practical form of device for carrying out the desired objects of the invention, and the operation of which will be readily understood without any extended explanation, since it is of course obvious that the fabric material 10, forming the covering or casing for the receptacle, or a lining for the same as in the case of the form of receptacle shown in Figure 5, will be maintained in a wet or damp condition throughout, so that the evaporation of the moisture which will constantly take place will necessarily produce a relatively lower temperature throughout the zone enclosed by said

covering or casing; this consequently produces the desired refrigerating effect, so long as the required supply of water is maintained within the chamber or chambers 15. The use of the cover 18 is desired in most cases, especially large receptacles, as the cover will, of course, be kept moist, thereby enhancing the cooling effect besides otherwise protecting the contents of the receptacle. A practical as well as inexpensive device is thus provided which is useful in all cases where a refrigerating or cooling device or attachment is desired, as, for example, for keeping liquids at a moderately low temperature, or for marketing purposes as represented by the type of receptacle shown in Figure 5, whereby the articles placed in the basket will be kept both moist, fresh and cool; and the improved device is one which will be found especially useful to touring or picnicking parties, as will be very readily understood. It is furthermore contemplated that the device itself may serve as the receptacle for the articles to be kept cool, since it would be convenient for use as a container for fruit and produce, and may be made in suitable portable form for the use of fruit and berry pickers for receiving the fruit and berries as they are gathered and preserving the same in a moist and fresh condition.

In Figures 8 and 9 I illustrate a modified form of top or closure construction 18' within which is provided a chamber 28 (equipped with a removable cap 17) for receiving a supply of water, and having channels 29 radiating from said chamber for distributing the water throughout the fabric material of which the closure or top 18' is made, thus providing for a more effective cooling action over the top of the receptacle or the articles to be cooled; this is more especially needed where large containers or receptacles are to be equipped with the improved device. This modified form of top is adapted to be secured to a receptacle by means of a draw string 19, the same as the type of top illustrated in Figure 2.

While I have illustrated and described what I now regard as practical and preferred forms of the invention, I desire to reserve the right to make such changes as may fairly fall within the scope of the following claims.

What I claim is—

1. A portable cooling device comprising a casing composed of fabric material adapted to receive the article or articles to be cooled, a part of the fabric material comprising said casing being formed as a closed water chamber adapted to receive a supply of water and feed the same gradually to the remainder of said material.

2. A portable cooling device comprising a receptacle composed of fabric material, a

part of the fabric material composing said receptacle being formed as an annular closed water chamber entirely surrounding the upper portion of the receptacle and adapted to receive a supply of water and feed the same gradually to the remainder of said material.

3. A portable cooling device comprising a casing composed of fabric material adapted to receive the article or articles to be cooled, a part of the fabric material compos-

ing said casing being formed as a closed water chamber adapted to receive a supply of water and feed the same gradually to the remainder of said material, and means within said closed water chamber for imparting 15 rigidity thereto.

In witness whereof I hereunto affix my signature.

JOHN L. TANDY.
